DRYING FIBERBOARD AND THE LIKE

Joseph F. Kiernan, Brooklyn, N. Y.

Application March 26, 1941, Serial No. 385,220

2 Claims. (Cl. 34—23)

This invention relates to fiber board and the like, and particularly to the drying of such board after fabrication.

The object of the invention is to provide a process for quickly and effectively drying the board without causing warpage due to inequalities in the drying effect.

Further objects of the invention particularly in accomplishing the drying without expensive mechanism or procedures will appear from the following specification taken in connection with the accompanying drawing in which

Fig. 1 is a vertical sectional view of apparatus showing a typical stage of the drying mechanism;

Fig. 1a is a sectional view on enlarged scale showing a detail of the roll and head parts in the apparatus of Fig. 1;

Fig. 2 is a similar view showing a modification; and

Fig. 2a is a sectional view on enlarged scale illustrating the cooperation between the roll and the surrounding shell structure.

Fiber board of bagasse, wood pulp and the like after fabrication into sheet form on screens or the like contains a large amount of moisture and must be dried before it is ready for shipment or use. The drying of this material is difficult and great care is required to subject pieces to even, uniform drying so as to avoid inequalities and irregularities which would cause an uneven shrinking effect and result in a warping of the material.

In prior operations the sheets of fiber board or the like are carried horizontally through long air drying chambers, for instance, on driven rollers, such as shown at 8 in Fig. 1 carrying the sheets of fiber board F and subjected to currents of hot air to carry off the moisture. The sheets are often one half an inch or more in thickness, and the tendency is for the outer earlier dried portions of the sheets to insulate the inner undried portions which are thus rendered very difficult to reach and long drying chambers and long times of exposure are required to reduce the moisture to desired degree while maintaining even drying conditions throughout each sheet.

In the process of this invention the sheets while being conveyed through the drying chamber are subjected to pressing contact above and below by members compressing the material to bring the successive fiber layers into more intimate contact with each other so that heat is conducted inward from each surface to the interior or core portions of the sheet. Then upon relief of the pressure the inner heated moisture

is free to expand outward through the still heated outer fibers of each surface of the sheet. This expansion as the stock leaves the roll also opens the fiber structure and gives access to relatively dry heated air from within the heated chamber permitting this air to penetrate into the pore spaces of the material. While in this position this heated air evaporates a percentage of the moisture of each fiber until it is compressively heated and exhaled at the following roll, this exhalation of evaporated moisture being augmented by the continued tendency of the inner heated moisture to expand outward through the still heated outer fibers of each surface of the sheet. In this way by making successive internal heat applications with intermediate expansion and drying of the material, the heat is conveyed rapidly into the material and the moisture expanded out. In most cases it will be desirable to heat the rolls themselves so as to conduct additional heat directly from the roll surfaces into the material.

In the apparatus illustrated diagrammatically in Fig. 1, sets of rolls 9 and 10 are substituted at intervals for the conveyor rolls 8, these rolls preferably being driven at peripheral speeds corresponding to the peripheral speeds of the conveyor rolls 8. The rolls preferably are heated for instance by steam or internal gas jets 12 as indicated or electrically where conditions warrant. The surfaces of these rolls 9 and 10 may be cylindrical as shown or undulated, corrugated or grooved to grip and irregularly press into the surface of the fiber board material as it passes. Between the heating stations hoods 14 may be provided kept under lower pressure to draw away the air and moisture from the surface of the sheets.

The inward flow of the air and moisture into the hood is illustrated in Fig. 1a showing the direction of the currents 15 drawing the gases over the surface of the fibers at the expansion stage following the roll compression and providing for a flow of the moisture laden air from directly under the roll to the vent pipe.

As illustrated in Fig. 2 the heated rolls 19, 20 may be supplied with hot dry air under pressure and provided with jet openings 21 permitting the escape of this drying air through the periphery of the roll cylinders into the material, the periphery of the roll not in contact with the material being housed in a shell 22 slidably closing the ports 21 and directing the escaping leakage air from opposite directions on to the upper and lower surface of the fiber board sheet. The shells 22 may be flanged outward as indicated at 23

carrying the heated currents along the surface of the board in each direction between the rolls. This will give a smooth engagement of the material with the shell in case there is any contact and preclude the possibility of the material being snagged or roughened by the sheet metal edge of the jacket and will spread the heated air currents over a large area of the material under treatment and for a longer period of time.

In all of these treatments of the material the fibers are pressed together and simultaneously heated so as to carry the heat down into the material from the pressing, heating surface. Then the release of the pressure opens the fibers and permits the volatilized vapors to escape and renders the surface accessible to the surrounding hot air of the drying chamber. The successive heatings concentrate the heat application along a narrow area giving a temporary high concentrated heating under pressure instead of the distributed relatively lower temperature air treatment of the prior art, and this temperature concentration of the heat combined with the pressing of the fibers together is quickly effective to transmit the heat into the interior of the fiber board and overcomes the insulating effect of the drying of the outer fibers.

The result is that with a uniform distribution of the heat and pressure across and along each sheet the heat is applied much more effectively and efficiently throughout all of the fibers. Time is saved and the length of the drying chamber reduced, and there is a corresponding increase

in the number of sheets dried within a given time.

I claim:

1. The process of drying fiber board comprising feeding said board endwise over supporting rollers, subjecting the surfaces of the board to heat and pressure along all portions of a transverse area extending crosswise of the board, simultaneously supplying currents of drying air to the surface of said sheet at said area, thus progressively bringing the successive fiber layers into more intimate contact with each other and conducting heat inward from each surface, and releasing the pressure on said surfaces to allow said surfaces to expand after the application of said compression, and thereafter circulating said air over the surfaces of the board as it expands to remove moisture therefrom.
2. In an apparatus for drying fiber board the combination of a series of sets of cooperating pressing rolls relatively superposed and contacting opposite faces of the board and compressing and feeding the board, certain of said rolls being hollow and peripherally perforated, and means for supplying air under pressure within said hollow rolls so as to force said air through said perforations and into the board throughout its surface under compression, said means comprising a member closing off the flow through such of said perforations as are not adjacent to said surface so that the air supply from said rolls is confined to the perforations adjacent the surface of said board.

JOSEPH F. KIERNAN.
